SAFETY DEVICE FOR A PROJECTILE

Harry H. Deringer, United States Navy,
Chesterstown, Md.

Application November 15, 1943, Serial No. 510,333

5 Claims. (Cl. 102—79)

(Granted under Title 35, U. S. Code (1952), sec. 266)

This invention relates to safety devices for a projectile adapted to be fired from a gun and provided with a firing pin adapted to strike a percussion cap with sufficient force to explode an explosive charge within the projectile as the projectile strikes the target, in which means are employed for preventing the premature firing of the explosive charge until the projectile has traveled a safe distance beyond the muzzle of the gun. More specifically the invention relates to a fuse for a projectile in which the firing pin is locked in a safe position with respect to the detonator until the projectile has attained a predetermined speed of rotation during the firing of the projectile from a gun and the force of acceleration of the projectile has diminished to a value corresponding to the force of acceleration acting on the projectile at a safe distance from the gun after the projectile has been fired therefrom.

In devices of this character heretofore devised for preventing the premature explosion of the projectile in or within the vicinity of the gun as the gun is fired, it has been the usual practice to employ a pair of cylindrical detents adapted to be moved outwardly within radially disposed tubular apertures disposed within the projectile and thereby remove a restraint from the firing pin and cause the projectile to be armed as the detents move radially outward by the centrifugal force acting thereon as the projectile is forced through the bore of the gun by the explosion of the main explosive charge. In the event that the detents should be moved to the unlocked position before the projectile has traveled beyond the muzzle of the gun, the force of acceleration acting on the movable firing member may cause the firing pin to strike the detonator with sufficient force to explode the projectile while the projectile is still within the barrel of the gun thereby damaging or destroying the gun and causing casualties to the gun crew and other personnel within the vicinity of the gun.

In accordance with the present invention this difficulty is overcome by employing a pair of locking detents in which the surfaces thereof comprise a pair of intersecting conic sections adapted to coact with complementary cam surfaces of the fuse support sufficiently to prevent movement of the detents outwardly to an unlocking position as the gun is fired until the force of acceleration of the projectile has decreased sufficiently to permit such movement.

One of the objects of the present invention is the provision of new and improved means for preventing the premature firing of an explosive charge within a projectile during the transportation, handling, loading and firing of the projectile from a gun.

Another of the objects is to provide a new and improved device for maintaining the firing pin of a projectile locked in a safe position as the projectile is fired from a gun until a predetermined relation between the acceleration of the projectile and the speed of rotation thereof about the axis of the projectile has been reached.

Another object is to provide a new and improved device

2

for preventing the premature firing of an explosive charge within a projectile in which the firing pin is locked in a safe position until the velocity of the projectile has reached substantially the maximum value after being fired from the gun and in which the locking means are maintained in the locking position by the force of acceleration of the projectile during the travel of the projectile through the gun.

A further object is to provide a new and improved device for locking the firing pin of a projectile in a safe position until the projectile is shot clear of the gun which is economical to manufacture, reliable in operation, and which possesses all of the desired qualities of ruggedness and durability.

Still other objects and advantages will be apparent from the following description taken in connection with the accompanying drawings of which:

Fig. 1 is a view in elevation and partially in section of a projectile employing the device of the present invention according to a preferred embodiment thereof;

Fig. 2 is a view somewhat enlarged and partially broken away taken substantially along the line 2—2 of Fig. 1;

Fig. 3 is an enlarged view of the fuse locking mechanism and partially in section showing the locking detents maintained in the unlocked position by centrifugal force as the projectile travels along a trajectory;

Fig. 4 is a view partially in section and partially broken away taken substantially along the line 4—4 of Fig. 3;

Fig. 5 is a greatly enlarged view in elevation of one of the locking detents employed with the device of Fig. 1; and,

Fig. 6 is a view in section and partially broken away of a locking detent and supporting means therefor in accordance with an alternative form of the invention.

Referring now to the drawings for a more complete understanding of the invention and more particularly to Fig. 1 thereof, there is shown thereon a projectile indicated generally by the numeral 10 having an annular

40 recessed portion 11 therein adapted to be engaged by a complementary portion of an explosive filled shell to which the projectile is secured during the transportation and loading of the shell into a gun, as is well known in the art to which the present invention pertains. The projectile is also preferably provided with an annular sleeve 12 of material suitable for the purpose such, for example, as brass adapted to be engaged by the rifling of the gun as the projectile is propelled outwardly therefrom by the firing of the explosive charge within the

45 projectile about the axis thereof as the projectile moves through the bore of the gun. The projectile is thus adapted to be propelled along a predetermined trajectory and to spin or rotate continuously about its axis throughout the trajectory as the result of the rotary movement imparted thereto by the rifling of the gun.

The projectile is also provided with a leading end or nose 13 composed of material suitable for the purpose such, for example, as zinc and secured to the main body

60 14 of the projectile in any suitable manner as by threading the parts together. The nose is provided with a circular well 15 having the axis thereof arranged coaxially with the axis of the projectile to which is secured in any suitable manner a bearing member or support 16 having a

65 shoulder 17 thereon adapted to engage a surface 18 formed within the nose of the projectile. Slidably disposed within the bearing member 16 is a firing pin 19 having an extending member 21 composed of any suitable material such, for example, as Bakelite secured thereto. The extending member 21 is adapted to drive

70 the firing pin rearwardly into engagement with a percussion cap or other suitable detonating device in response

to the crushing of the nose of the projectile as the projectile strikes the target. It will, of course, be understood that if desired the projecting member 21 may be made of the same material as the firing pin and, furthermore, the firing pin and projecting member may be of integral construction.

The support 16 is provided with a pair of diametrically arranged apertures 22 within which is respectively disposed a pair of locking detents 23 adapted to be releasably maintained in engagement with a reduced cylindrical portion 24 of the firing pin by a circular spring 25 encircling the detents and adapted to urge the detents yieldably and inwardly against the firing pin, a chamber 26 being provided within the nose of the projectile of sufficient size to permit the spring 25 to expand and thereby release the detents from the locking position thereof, as will more clearly appear as the description proceeds.

The locking detents comprise two intersecting conic frustums 27 and a pair of cylindrical surfaces 28, Fig. 5, the ends of the detents being preferably conic sections whereby the pressure of the spring 25 against each of the detents is applied along a line intersecting the axis of the detent. In like manner the pressure of the detent against the cylindrical portion 24 of the firing pin is applied along a line intersecting the axis of the detent. The detent is adapted to be engaged at the surface of one of the conic frustums 27 by a shoulder 29 on the support 16 formed by an orifice within the support of sufficient size to permit sliding movement of the firing pin therethrough when the firing pin has been unlocked from a safe position by movement of the detents 23 from the path of travel of the firing pin. With the detents in the locking position, Fig. 1, the firing pin is maintained locked in a safe position and prevented from being brought into contact with the detonator by reason of the engagement of a cylindrical portion 28 of each of the detents with the shoulder 31 on the firing pin.

As the projectile travels through the bore of the gun in response to the firing of the gun, the firing pin including the extending member 21 is urged toward the rear of the projectile by the force of acceleration applied thereto by the shoulder 29 on the support 16 and the detents aforesaid. This force resulting from the acceleration of the projectile in response to the expansion of the gases within the gun is applied in a direction along the path of travel of the projectile and is hereinafter referred to as a setback force. This setback force decays rapidly as the projectile leaves the muzzle of the gun and attains zero value when the maximum velocity of the projectile is reached. It will be readily understood from an inspection of the arrangement of the various parts of Fig. 1 that the setback force of the firing pin applied to the detents effectively prevents the outward radial movement of the detents from the initial locking position thereof by reason of the engagement of the conic frustums or sections 27 with the shoulder 29 of the support 16.

As the projectile is propelled along the bore of the gun by the explosive blast, the rifling of the bore engages the sleeve 12 and imparts rotative movement to the projectile thereby causing the detents to be spun rapidly about the axis of the projectile and a centrifugal force to be generated thereby in accordance with the law of centrifugal force applied to rotating masses. This force, as is well known, is proportional to the product of the mass and the square of the velocity and inversely proportional to the radius of curvature and may be conveniently expressed by the formula

$$f = \frac{mv^2}{r}$$

This force is of sufficient strength to overcome the tension in the spring 25 and to cause the detents to move outwardly to an unlocking or armed position and clear of the path of travel of the firing pin. The detents, however, are prevented from being moved outwardly to the

unlocking position by the setback force applied thereto by the firing pin until the projectile has moved a safe distance beyond the muzzle of the gun, at which distance the setback force is reduced sufficiently for the centrifugal force of the detents to move the detents outwardly into the armed position thereby unlocking the firing pin and arming the projectile. As the detents move outwardly into the armed position, the firing pin is moved slightly forward with respect to the nose of the projectile by reason of the movement of the conic surfaces 27 of the detents against the shoulder 29 of the support 16.

As the gun is fired the initial movement of the projectile away from the shell is a motion of translation and when the projectile has moved a predetermined distance within the bore of the gun, the sleeve 12 engages the rifling of the bore and rotation of the projectile is initiated thereby. From the foregoing, it will be apparent that the setback force is applied to the projectile prior to the rotative movement thereof and thus the detents are effectively locked in the locking position thereof by the setback force before the centrifugal force comes into play, thereby providing an arrangement in which there is no possibility of prematurely arming the projectile until the projectile has safely cleared the gun and the setback force has decreased to a value insufficient to cause the firing pin to strike the detonator and explode the projectile as the detents move into the unlocking or armed position.

On Fig. 3 is shown the detents maintained in their unlocking or unarmed position by centrifugal force during the travel of projectile along a trajectory, the spring 25 being expanded into engagement with the cylindrical wall of the chamber 26. The projectile is thus armed when the setback force of the firing pin 19 is insufficient to overcome the centrifugal force of the locking members and the firing pin, therefore, is in readiness to be driven against the detonator by the force of impact received as the projectile strikes the target.

On Fig. 6 there is shown one of a pair of locking detents 32 and the supporting means therefor in accordance with an alternative form of the invention. The detent 32 is generally similar to the detent 23 and may, if desired, be used in the same structure employed in connection with the detents 23. The detent 32, in the specific form illustrated, comprises a pair of cylindrical surfaces 33 in abutting relation with a pair of conic frustums 34, the conic frustums being connected by a cylindrical surface 35. The ends of the detent are preferably formed in a manner similar to the detent 23 and adapted to be engaged by the spring 25 and the firing pin 19 at the reduced cylindrical portion 24 thereof. The operation of the detents 32 is generally similar to the operation of the detents 23, the detents being yieldably maintained in the locking position by the spring 25 and by the setback force of the firing pin 19 until the projectile has moved a safe distance beyond the muzzle of the gun at which time the setback force is reduced sufficiently to permit the detents to be moved radially outward by the centrifugal force acting thereon and thereby arm the projectile.

While the invention has been described with particularity in reference to two embodiments disclosed, it will be apparent to those skilled in the art to which the invention pertains, after understanding the invention, that the invention in its broader aspect could be carried out by other instrumentalities, and it is understood that the terms used in the claims are words of description and not of limitation except as necessitated by the prior art.

The invention herein described and claimed may be manufactured and used by or for the Government of the United States of America for governmental purposes without payment of any royalties thereon or therefor.

What is claimed as new and desired to be secured by Letters Patent of the United States is:

1. A safety device for a projectile adapted to be fired from a gun and having an explosive charge therein, means including a firing pin slidably and coaxially arranged

within said projectile and having a stop member thereon, a striker on the firing pin adjacent said stop member and adapted to fire said explosive charge, said striker having a cylindrical portion thereon, a cylindrical bore disposed within the projectile with the axis thereof intersecting the axis of the striker, a pair of detents respectively arranged within said bore on opposite sides of said striker and adapted to be tilted within the bore and moved from an initial safe position to an armed position by centrifugal force during the travel of the projectile along a trajectory, each of said detents having a pair of abutting frustum portions adapted to impart a driving force to the firing pin as the detents move from said safe position to said armed position and a pair of cylindrical portions respectively intersecting the bases of the frustum portions and a pair of conical surfaces respectively arranged on the end portions of the cylindrical portions thereof in intersecting relation with the cylindrical portions, means forming a circular chamber within the projectile in communication with the outer ends of said bore and having the axis thereof in alignment with said striker, a substantially cylindrical resilient member disposed within said chamber and adapted to urge the detents yieldably against the striker by pressure applied thereby, the conical surfaces on the ends of the detents being so proportioned as to apply said pressure along a line of contact between each of the detents and the resilient member and a second line of contact between each of the detents and the cylindrical portion of the striker when the detents are tilted within said bore, each of said lines of contacts being parallel to the striker, and means on the projectile arranged adjacent the striker and adapted to coact with the inner frustum portions of the detents for preventing outward movement of the detents by centrifugal force as the projectile is fired from the gun until the setback force of the firing pin has decreased sufficiently to permit the firing pin to be moved forwardly by the driving force imparted thereto by said frustum portions as the detents move outwardly to said armed position.

2. A safety device for a projectile adapted to be fired from a gun and having an explosive charge therein, means including a firing pin slidably and coaxially arranged within said projectile and having a stop member thereon, a striker on the firing pin adjacent said stop member and adapted to fire said explosive charge, said striker having a cylindrical portion thereon, a cylindrical bore disposed within the projectile with the axis thereof intersecting the axis of the striker, a pair of detents respectively arranged within said bore on opposite sides of said striker and adapted to be tilted for pivotal movement within the bore and moved from an initial safe position to an armed position by centrifugal force during the travel of the projectile along a trajectory, a pair of conical surfaces respectively arranged on the end portions of said detents, means forming a circular chamber within the projectile in communication with the outer ends of said bore and having the axis thereof in alignment with said striker, an annular resilient member disposed within said chamber and adapted to urge the detents yieldably against the striker by pressure applied thereby, the conical surfaces on the ends of the detents being adapted to apply said pressure along a line of contact between each of the detents and the resilient member and a second line of contact between each of the detents and the cylindrical portion of the striker when the detents are tilted within said bore, each of said lines of contacts being parallel to the striker, and means arranged adjacent the striker for preventing outward movement of the detents by centrifugal force as the projectile is fired from the gun until the setback force of the firing pin has decreased sufficiently to permit pivotal movement of the detents to drive the firing pin forwardly.

3. A safety device for a projectile adapted to be fired from a gun and having an explosive charge therein, a firing pin slidably and coaxially arranged within said projectile, a stop member arranged on said firing pin, a striker con-

centrically formed on said stop member and having a cylindrical portion thereon, a cylindrical bore disposed within the projectile, a pair of detents respectively arranged within said bores on opposite sides of said striker and adapted to be tilted within the bore and moved from an initial safe position to an armed position by centrifugal force during the travel of the projectile along a trajectory, a pair of frustum portions on each of said detents adaptable to impart a driving force to the firing pin as the detents move from said safe position to said armed position, a pair of cylindrical portions respectively intersecting the bases of the frustum portions, a pair of conical surfaces respectively arranged on the end portions of said detents in intersecting relation with the cylindrical portions thereof, means forming a circular chamber within the projectile, an annular resilient member disposed within said chamber and adapted to urge the detents yieldably against the striker by pressure applied thereby, said conical surfaces being so proportioned as to apply said pressure along a line of contact between each of the detents and the resilient member and a second line of contact between each of the detents and the cylindrical portion of said striker when the detents are tilted within said bore, and means on the projectile adapted to coact with the inner frustum portion of each of the detents for preventing the detents from being moved to said armed position by said centrifugal force until the setback force of the firing pin has decreased sufficiently to permit the firing pin to be cammed forwardly by the driving force imparted by said frustum portions as the detents move outwardly to said armed position.

4. In a safety device for a projectile adapted to be fired from a gun and having an explosive charge arranged within said projectile, in combination, a support arranged within said projectile, a firing pin slidably arranged within said support and having a stop member thereon, a striker on the firing pin adjacent said stop member and adapted to fire said explosive charge upon impact of the projectile with a target, a cylindrical bore disposed within the support with the axis thereof intersecting the axis of the striker, a pair of detents respectively arranged within said bore on opposite sides of said striker, said detents being adapted to be tilted within the bore and moved from an initial safe position to an armed position by centrifugal force, each of said detents having a pair of abutting frustum portions thereon adaptable to impart a driving force to the firing pin as the detents move from said safe position to said armed position, a pair of cylindrical portions respectively intersecting the bases of the frustum portions and a pair of conical surfaces respectively arranged on the end portions thereof in intersecting relation with the cylindrical portions, means forming a circular chamber within the projectile in communication with the outer ends of said bore and having the axis thereof in alignment with said striker, an annular resilient member disposed within said chamber and adapted to urge the detents yieldably against the striker by pressure applied thereby, said conical surfaces on the ends of the detents being adapted to apply said pressure along a line of contact between each of the detents and the resilient member and a second line of contact between each of the detents and the striker when the detents are tilted within said bore, each of said lines of contacts being parallel to the striker, and means on the support arranged adjacent the striker and adapted to coact with the inner frustum portion of each of the detents for preventing outward movement of the detents by centrifugal force as the projectile is fired from the gun until the setback force of the firing pin has decreased sufficiently to permit the firing pin to be moved forwardly by the driving force imparted by said frustum portions as the detents move outwardly to said armed position.

5. In a safety device for an explosive shell adapted to be fired from a gun, in combination, a nose secured to said shell and having a centrally disposed bore therein in communication with a circular well, said bore and well

being arranged coaxially with respect to the axis of the shell, a support secured to said nose, and disposed within said well and having a shoulder thereon adapted to engage the forward wall defining the well, a bearing member on said support and in abutting engagement with the wall defining said bore, and having a cylindrical bearing surface centrally disposed therein, a firing pin, a stop member on said firing pin and slidably arranged within said bearing surface, a striker formed on one end of said stop member, an impact member secured to the other end of the stop member and adapted to drive the striker into firing engagement with said explosive shell upon impact of the shell with a target, said striker having a cylindrical portion thereon, said support having a transverse cylindrical opening extending therethrough with the axis thereof intersecting the axis of the striker, a pair of detents respectively arranged within said opening on opposite sides of said striker and adapted to be tilted within the opening and moved from an initial safe position to an armed position by centrifugal force as the shell travels along a trajectory, each of said detents having a pair of abutting frustum portions adapted to impart a driving force to the firing pin as the detents move from said safe position to said armed position and a pair of cylindrical portions respectively intersecting the basis of the frustum portions and a pair of conical surfaces respectively arranged on the end portions thereof in intersecting relation with the cylindrical portions, an annular resilient member arranged within said well and adapted to urge the detents yield-

ably against the striker by pressure applied thereby, the conical surfaces on the ends of each of the detents being adapted to apply said pressure along a line of contact between the detent and the resilient member and a second line of contact between the detent and the striker when the detents are tilted within said transverse opening, each of said lines of contacts being parallel to the striker, and means on the support arranged adjacent the striker and adapted to coact with the inner frustum portion of each of the detents for preventing outward movement of the detents by centrifugal force as the projectile is fired from the gun until the setback force of the firing pin has decreased sufficiently to permit the firing pin to be cammed forwardly by the driving force of said frustum portions as the detents move outwardly to said armed position.
